UNITED STATES PATENT OFFICE.

CHARLES LEFKOWITZ, OF NEWARK, NEW JERSEY.

CARBOY.

Application filed August 31, 1923. Serial No. 660,396.

To all whom it may concern:

Be it known that I, CHARLES LEFKOWITZ, a citizen of the United States, residing in the city of Newark, in the county of Essex 5 and State of New Jersey, have invented a new and Improved Carboy, of which the following is a full, clear, and exact description.

My invention has for its object to provide a carboy which may be made strong, 10 light in weight, inexpensive to construct, and with a minimum amount of material.

Still another object of the invention is to provide a carboy with lateral supporting 15 members for a bottle, the lateral supporting members having shoulder blocks at their ends which abut against inner portions of the carboy. The shoulder blocks which abut against the inner portions of the carboy 20 prevent the movement of the lateral supporting members horizontally parallel with the adjacent side of the carboy body, the lateral supporting members being held outwardly in position by a bottle disposed 25 in the carboy. While the lateral supporting members will therefore be held in position when in use, should they become damaged, they may be readily raised out of the body of the carboy to permit of their 30 replacement.

Additional objects of the invention will appear in the following specification in which the preferred form of my invention is described:

35 In the drawings,

Fig. 1 illustrates in perspective a carboy constructed in accordance with this invention, parts of the carboy being broken away; and,

40 Fig. 2 is a plan view of a modified form of the carboy.

In Fig. 1 of the drawings a carboy body is shown at 5, this carboy body having inner corner pieces 6 such as are usually provided for holding the sides 7 of the carboy body in position and relatively to each other. Disposed within the carboy body there are lateral supporting members 8 for the bottle which will be disposed in the 45 carboy body. These lateral supporting members may be constructed in any desired manner but they are preferably constructed of horizontal pieces 9, which are connected by vertically extending pieces 10. I prefer to use two vertically extending pieces 50 10 for each of the lateral supporting mem-

bers, these vertically extending pieces 10 being preferably spaced apart so that when the bottle is disposed in the carboy body, they will engage the bottle. In every case 60 the lateral extending members 8 have shoulder blocks 11 at their ends to engage the inner surfaces of the carboy body 5. In the construction illustrated in Fig. 1 of the drawings these shoulder blocks 11, engage 65 the corner pieces 6 but they may be constructed to engage other portions of the carboy body as will be hereinafter described.

It will be understood that the lateral supporting members 8 will be held outwardly 70 by the bottle disposed in the carboy body 5 and that they will be prevented from moving horizontally parallel with the sides 7 of the carboy body by the shoulder blocks 11 which abut against the corner pieces 6. 75 Therefore, the lateral supporting members which are engaged by the bottle contained in the carboy body will support the bottle laterally in accordance with the requirements. While this is so, when the bottle 80 has been removed from the carboy body 5, any one or all of the lateral supporting members 8 may be readily raised from the carboy body for replacement should one or more of the lateral supporting members be 85 damaged in transportation.

In the construction illustrated in Fig. 2 of the drawings, the carboy body is constructed as has been described. However, in the Fig. 2 of the drawings the shoulder 90 blocks 11^a are triangular in cross section and they engage the interior of the carboy body between the corner pieces 6. In other respects the construction of the lateral supporting members 8^a corresponds with the 95 construction of the supporting members 8 which are shown in Fig. 1 of the drawings.

The shoulder blocks 11^a prevent the horizontal movement of the lateral supporting members 8^a in the longitudinal plane in 100 which they are disposed, the bottle shown by the dotted lines 12 in Fig. 2 of the drawings serving to prevent the inward movement of the lateral supporting members 8^a. As will be seen in Fig. 2 of the drawings the 105 vertically extending members 10^a of the lateral supporting members 8^a engage the bottle shown by the dotted lines at 12.

Having thus described my invention what I claim as new and desire to protect by Letters Patent is:

1. In a carboy, a complete hollow body

- with means for holding the parts together, four lateral supporting members in the hollow body, and vertical shoulder blocks free from each other and free from the hollow body secured one at each end to each of the lateral supporting members, the shoulder blocks having extending surfaces which abut against the hollow body, the lateral supporting members with the shoulder blocks being removable from the hollow body.
2. In a carboy, a complete hollow body with means for holding the parts together, four removable, horizontally disposed, lateral supporting members in the hollow body disposed to form an angular figure and vertical shoulder blocks free from each other, secured one to each end of each of the lateral supporting members at their outer surfaces which abut against the hollow body.
3. In a carboy, a complete hollow body with means for holding the parts together, a plurality of lateral supporting members in the hollow body and shoulder blocks triangular in cross section secured one at each end of each of the lateral supporting members at their outer surfaces, a surface of each shoulder abutting against the inner face of the hollow body, the lateral supporting members with the shoulders being removable from the hollow body.
4. In a carboy, a hollow body, angular in cross section, a plurality of lateral supporting members disposed in the hollow body, each end of each lateral supporting member being disposed between and spaced from two corners of the hollow body, and shoulder blocks triangular in cross section, free from each other, the outer faces of the lateral supporting members at their ends being secured to faces of the shoulder blocks,
- and other faces on the shoulder blocks abutting against the hollow body, the lateral supporting members and the shoulder blocks being removable from the hollow body.
5. In a carboy a complete hollow body with four vertical corner posts, each corner post having two inner sides, a plurality of lateral supporting members in the hollow body and eight vertical shoulder blocks, one disposed at each of the said sides of the corner posts, the lateral supporting members having their ends secured to the shoulder blocks and being removable therewith from the hollow body.
6. In a carboy, a complete hollow body with four vertical corner posts, each post having two inner sides, a plurality of lateral supporting members in the hollow body, and eight vertical shoulder blocks, one disposed at each of the said sides of the corner post, the lateral supporting members being removable and being secured at their outer faces adjacent their ends to the shoulder blocks to space the lateral supporting members from the sides of the body.
7. In a carboy, a rectangular hollow body, four lateral supporting members disposed obliquely in the hollow body, each end of each lateral supporting member being disposed between and spaced from two corners of the hollow body, and shoulder blocks triangular in cross section, free from each other, the outer faces of the lateral supporting members at their ends being secured to faces of the shoulder blocks, with other faces on the shoulder blocks abutting against the hollow body, the lateral supporting members and the shoulder blocks being removable from the hollow body.

CHARLES LEFKOWITZ.
